Primary Examiner — Dominic V Simone(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a front view thereof; and,

FIG. 3 is an opposite side front perspective view thereof. The uneven-length broken line immediately adjacent to the shaded area in the toe region defines the bounds of the claimed design and form no part thereof. The even-length broken lines within the shaded areas represent stitching which forms no part of the claimed design. The uneven-length broken lines depicting the remainder of the shoe form no part of the claimed design.
